UNITED STATES PATENT OFFICE.

ELI W. KNOWLES, OF FRANCISCO, ASSIGNOR OF ONE-HALF TO FRANKLIN M. KNOWLES, OF OWENSVILLE, INDIANA.

LAND-ROLLER.

SPECIFICATION forming part of Letters Patent No. 335,077, dated January 26, 1886.

Application filed July 30, 1885. Serial No. 173,038. (No model.)

To all whom it may concern:

Be it known that I, ELI W. KNOWLES, a citizen of the United States, and a resident of Francisco, in the county of Gibson and State 5 of Indiana, have invented certain new and useful Improvements in Land-Rollers; and I do hereby declare that the following is a full, clear, and exact description of the invention, which will enable others skilled in the art 10 to which it appertains to make and use the same, reference being had to the accompanying drawings, which form a part of this specification, and in which—

Figure 1 is a top view of my improved 15 land-roller. Fig. 2 is a vertical transverse sectional view of the same, taken through the axle on which the roller or rollers are mounted. Fig. 3 is a longitudinal vertical 20 sectional view taken on the line *x x* in Fig. 2, and Figs. 4 and 5 are detail views of two of the disks of which the rollers are composed.

The same letters refer to the same parts in all the figures.

This invention relates to land-rollers, and 25 it has for its object to provide a device of this class which shall possess superior advantages in point of simplicity, durability, and general efficiency, which may be constructed at a moderate expense, and which shall serve to crush 30 the clods and level the soil more effectively than rollers of ordinary construction.

With these ends in view the invention consists in the improved construction, arrangement, and combination of parts, which will be 35 hereinafter fully described, and particularly pointed out in the claim.

In the drawings hereto annexed, A designates the rectangular frame in which the roller is mounted, to the front beam of which is attached the tongue or draft-bar B.

C is the roller, which consists of a cylindrical body having a series of annular grooves, D D, separated by flanges E E. This roller, which may be made of wood, metal, or any 45 other suitable material, is preferably constructed, as shown in the drawings hereto annexed, of a series of disks, F and G, the former of which are all of one size, but larger

than the latter, which are also all of one size. These disks are placed together, alternating 50 with each other, as will be seen in the drawings, and connected securely by means of transverse bolts H H, so as to form a solid and substantial roller-body. The several disks are provided with central perforations, I, registering 55 with each other, and forming a bearing for the axle J, on which the roller is mounted, and which is in turn journaled in the sides of the frame A. The sides of the larger disks, F F, are provided at some distance from their 60 peripheries with annular grooves K, adapted to receive annular flanges L, extending from the peripheries of the smaller disks, G G. By this construction the strength and durability of the roller are greatly increased, and close 65 joints are formed between the several disks. When the disks are made of wood, the flanges upon the smaller disks may be in the nature of tires, of metal or other suitable material, bolted or otherwise secured to the rims of the 70 said disks.

One or more of my improved rollers may be mounted upon the axle of the machine, and when more than one are used washers M are to be interposed between the several rollers. Similar washers M are also to be placed 75 upon the axle between the ends of the outer rollers and the sides of the frame.

N is a cross-bar secured to the sides of the frame in rear of the roller or rollers, and provided with a series of teeth, O, that enter the annular grooves D of the said rollers, for the purpose of keeping them clear of dirt during the operation of the machine.

From the foregoing description, taken in 85 connection with the drawings hereto annexed, the operation and advantages of this invention will be readily understood.

The construction is simple and inexpensive, and the flanges of the roller will serve effectively to crush the clods and pulverize the soil.

Having thus described my invention, I claim and desire to secure by Letters Patent of the United States—

In a land-roller, the herein-described roller, 95 composed of a series of disks the sides of

which are provided with annular grooves at some distance from their peripheries, alternating with a series of smaller disks the peripheries of which have laterally-extending flanges that enter the grooves in the larger disks, said disks being secured together, substantially as and for the purpose herein set forth.

In testimony that I claim the foregoing as my own I have hereunto affixed my signature in presence of two witnesses.

ELI W. KNOWLES.
